Letter Patent

The Machine referred to in these Letter Patent and making part of the same, containing a description in the words of the said Leonard Morris himself, of his improvement in an accelerated Spinner.

To all to whom these presents shall come. Be it known that I, Leonard Morris of Chafield in the County of Oxford and State of Maine have invented a new and useful improvement in an accelerated Spinner and that the following is a full and exact description of the construction and operation of said machine as invented by me - Specification. The spinner is constructed in the following manner. 1st A Bench two feet and a half long and six or eight inches wide one or two inches thick with a small clamp on the side for the purpose of fastening it to the edge of the table or light stand or chair. 2nd A foot at one end ten inches high with a box for a mouth of a shaft to run in. At the other end a foot fifteen inches high and about the width of the bench in which the other end of the shaft and spindle are hung. 3rd A Draft of about the length of the bench with a mouth of about six inches in length upon one end and a cog wheel near the other and hung in the foot which has been mentioned about seven inches from the bench. 4th A cog wheel about one foot in diameter with sixty or more cogs and a spur wheel with cogs shaped to mesh into a screw. 5th The spindle is about the size and length of other spinning wheel spindles. The whorl is placed near the large end and directly over the center of the cog wheel. The whorl is made in the form of a screw with a thread that will fit the cog in the wheel. The large end of the spindle is reduced near the end nearly to a point and hangs as a foot in a carabon near the edge of the wide foot. Near the other edge of the foot is a box in which the spindle hangs. The spindle is so constructed as not to work under this improvement consisting of the above described parts to turn a spindle for the purpose of spinning in the manner above specified for which I apply for Letter Patent January 7th 1835.
